STORAGE CONTAINER FOR FISHING HOOKS AND LEADERS

John Luther Herring, 2626 S. 48th Terrace,
Kansas City, Kans. 66106

Filed June 18, 1973, Ser. No. 370,954

Term of patent 14 years

Int. Cl. D9—03

U.S. Cl. D9—235

FIG. 2.

FIG. 4.

FIG. 1 is a perspective view of a storage container for fishing hooks and leaders showing my new design in open position;

FIG. 2 is a top plan view;

FIG. 3 is a side elevational view; and

FIG. 4 is an end elevational view.

I claim:

The ornamental design for a storage container for fishing hooks and leaders, as shown and described.
